(74) Attorney, Agent, or Firm — Jeffrey Roddy

(57) **CLAIM**

The ornamental design for a floor scrubber, as shown and described.

DESCRIPTION

FIG. 1 is a top plan view of my new design for a floor scrubber that shows a flexible pad, an elastic band, and a fabric tab;

FIG. 2 is a front, left perspective view thereof;

FIG. 3 is a bottom plan view thereof;

FIG. 4 is a bottom, left perspective view thereof;

FIG. 5 is a front elevation view thereof;

FIG. 6 is a left side elevation view thereof; and,

FIG. 7 is a perspective view in an environment of use.

The broken lines in the drawings depict environment of the floor scrubber and forms no part of the claimed design.
